METHOD OF AND APPARATUS FOR AP-
PLYING A FLEXIBLE SHEET TO A RE-
CEPTACLEThomas H. Nifong, Winston-Salem, N. C., as
signor of one-half to George Agee, Winston-
Salem, N. C.

Application May 6, 1935, Serial No. 20,100

51 Claims. (Cl. 216—29)

My invention relates to a method of and apparatus for applying a flexible sheet or strip to a receptacle, for effecting an air tight joint between the closure element and body portion of 5 the receptacle.

An important object of the invention is to provide apparatus for applying the sealing sheet or tape to receptacles or cans having shapes other than round, such as flat tobacco cans.

10 A further object of the invention is to provide a machine of the above mentioned character which will hold the sealing sheet or tape taut, prior to and during its application to the can, whereby the tape will effect an air tight joint 15 between the lid or top and body portion of the can.

15 A further object of the invention is to provide a machine of the above mentioned character which will first apply an adhesive to the tape, then transfer the tape to the can or receptacle, cut the applied tape from the remainder of the tape, and subsequently roll or iron the applied tape for providing a smooth tight joint.

20 A further object of the invention is to provide a machine of the above mentioned character which is automatic in operation and will rapidly apply the sealing tape or sheet to the cans.

25 Other objects and advantages of the invention will be apparent during the course of the following description.

30 In accordance with the practice of my method, a sealing tape or strip is employed, which is preferably formed of transparent material, so that it will be substantially invisible when applied to a can or receptacle. The tape or strip may be formed of "Cellophane", although other material may be employed. While it is preferred to have the tape or strip transparent, yet in some instances it may be translucent, or even opaque.

35 The sealing tape has a fluid adhesive applied to a suitable length of the same, and the portion of the tape thus treated is held taut. The can or like receptacle to be treated is supported and held on end and is shifted into the operative 40 position and is then held stationary. The leading end of the tape having the adhesive applied thereto, the adhesive not as yet having dried or set, is now brought into contact with the then stationary can, at the line of engagement between the body and top or cover of the can.

45 The can thus supported on end with the leading end of the tape in engagement therewith, is now turned for substantially a complete revolution, while contacting with the taut tape. While this 50 is done, pressure is applied to the top or lid of

the can so that it will be securely seated, whereby the tape will effect an air tight joint between the top or lid and body portion. After the length of tape having the adhesive thereon is thus applied to the can, the applied length of 5 tape is cut from the remainder of the tape, and the cutting and application of the tape is such that the ends of the applied tape are slightly overlapped. Immediately following this operation, the applied tape is subjected to a rolling 10 or ironing action which firmly presses, smooths, and bonds the same to the can, prior to the final setting or drying of the adhesive. The adhesive is then allowed to completely dry or set and the operation is completed. 15

It is thus seen that the receptacle or can is bodily supported on end, and pressure is applied to the top or lid of the can, whereby the can is securely clamped to the element holding the can. The pressure applied to the lid or top 20 of the can also serves to hold the lid or top firmly seated, thereby aiding in the proper sealing operation. By supporting and advancing the can on end, the movement of the can is not dependent upon its shape in cross-section and 25 cans of varying shapes in cross-section, including circular and other than circular, may be properly treated by my method and apparatus.

In the accompanying drawings forming a part 30 of this application and in which like numerals are employed to designate like parts throughout the same,

Figure 1 is a side elevation of a machine embodying my invention.

20 Figure 14a is a detailed section through the sliding supporting connection of the adhesive receptacle.

In the drawings, wherein for the purpose of 25 illustration is shown a preferred embodiment of my invention, the numeral 20 designates a table top supported by frame legs 21. Arranged near and above the table top 20 is a rotatable support 22, preferably in the form of a spider and including 30 a hub 23 and radial arms 24. This hub is rigidly mounted upon a vertical shaft 25 which is rotatable within a sleeve 26, to be more fully described. The sleeve 26 is rotatable within a bearing sleeve 27, rigidly attached to the table top 20, as shown at 28. At its lower end, the vertical shaft 25 is journaled in a stationary bearing 29, carried by stationary arms 30 or the like. These arms 30 are bolted to the table top 20. The spider arms 24 are provided at their outer ends 35 with bearings 31, receiving vertical stub shafts 32, carrying at their upper ends can receiving and holding devices 33, which are rigidly attached thereto. Each of these devices embodies a preferably circular bottom 34 and an upstanding strip 35, which is generally U-shaped in cross-section. The strip 35 is of course rigidly attached to the bottom 34 and forms therewith a pocket to receive the can 36. The trailing side 37 of the strip 35 is longer than the leading side 38, as more 40 clearly shown in Figures 4, 5 and 6. The invention is in no sense restricted to the particular shape of the holding device as it must be varied to accommodate the particular can or receptacle to be held thereby. The holding device is shaped 45 for the purpose of illustration for receiving a flat tobacco can.

Means are provided to turn the can holding devices upon their vertical axes, during a portion of their travel with the spider, and also to lock 50 them against such turning movement, during a portion of the same. To effect this operation, a gear 39 is rigidly mounted upon the lower end of each vertical stub shaft 32, and each gear 39 is provided at its bottom and projecting below 55 the same with a cylindrical lug or boss 40, having a portion of one side cut away to provide a locking face 41, which is concave, for a purpose to be described. The numeral 42 designates an operating member including a hub 43, preferably 60 integral with the sleeve 26. Secured to the hub 43 are radial arms 44, to which are rigidly secured a rim including a circularly curved rack 45 and a circularly curved locking bar 46. The rack 45 is disposed above the locking bar 46, and the rack 45 engages with the gear 39, while the

locking bar 46 is adapted to engage with the locking faces 41, and these locking faces have the same circular curvature as the locking bar 46. The means to move the operating member will be described later.

5 A conveyor mechanism 47, Figures 2, 3 and 11, is provided to feed a can into each holding device as it is brought to the filling position. This conveyor mechanism comprises a stationary bottom 48, rigidly mounted upon the upper ends of 10 arms or brackets 49, which in turn are secured to the table top 20. If desired, the outer end of the bottom 48 may be further supported by means of brackets 50, having elongated slots 51, to receive a shaft 52. This shaft is supported by a 15 forked arm 53, vertically arranged, and pivotally supported at 54. The arm 53 is swung in one direction by a spring 55, attached thereto and to a bracket 56. The swinging movement of the arm 53 does not perceptibly move the bottom 20 48, which will be supported against downward movement by the shaft 52. The numeral 57 designates an endless conveyor belt, the upper run of which travels upon the upper surface of the bottom 48, and this conveyor belt passes over 25 a pulley 58, carried by the shaft 52 and pulley 59 carried by a shaft 60, journaled in bearings formed in the arms or brackets 49. The pulley 59 is rigidly mounted upon its shaft 60 to turn therewith. The means for driving the shaft 60 30 will be described later. The conveyor mechanism further comprises stationary sides 61 and 62, which are rigidly attached to the bottom 48. The side 62 may be termed the leading side with relation to the direction of turning movement of 35 the spider, and the inner end of the side 62 is foreshortened with respect to the side 61 and carries a swinging clamping jaw 63, hinged thereto, as shown at 64, and swinging in a horizontal plane toward and from the side 61, the adjacent portion of the side 61 constituting a stationary 40 jaw of a clamping device. The jaw 63 is swung inwardly by a retractile coil spring 65, attached to a pin 66 secured to the jaw 63 and a pin 67 secured to the side 61. Arranged beneath the bottom 48 and near the inner end of the same 45 is a horizontally swinging lever 68, pivoted to the bottom at 69 and carrying at its inner free end a roller 70. Pivotal connected with the lever 68 between its ends is a link 71, pivoted to a pin 72, secured to the movable jaw 63. Each spider arm 24 is provided upon its outer end and adjacent to the bearing 31 with a cam 73, to engage the roller 70 and thereby shift this roller and its lever 68 laterally, whereby the jaw 63 will be 50 swung outwardly in opposition to its spring, to release the leading can. It may be stated at this point that the endless belt 57 is travelling continuously, and the intermittent feeding of the cans is effected by holding the leading can 55 against advancing movement by the clamping device including the jaw 63, and releasing the leading can as the next can holding device is brought to the proper can receiving position. When the leading can is released by the clamping device, the weight of the cans on the conveyor belt 57 60 will cause the cans to travel with the conveyor belt, but when the leading can is held against movement by the clamping device, the belt will slip under the cans without effecting their feeding movement.

65 Means are provided to engage the top or lid of the can after it has been completely moved into the can holding device and before it has reached the tape applying position, to firmly press the

lid or cover seated upon the can and to securely clamp the can in the holding device, against accidental displacement. This means comprises a spider bearing device 74, rigidly mounted upon the upper end of the vertical shaft 25, and carrying sockets 75, corresponding in number and arrangement to the arms of the spider. Vertical rods 76 have their upper ends slidably mounted within the sockets and are forced downwardly by compressible coil springs 77. These rods have their lower portions operating within guide bearings 78, formed upon the spider arms 24. Rigidly mounted upon the rods 76 are radial arms 79 carrying tubular heads 80, rotatably receiving presser elements 81, the can engaging ends of which are preferably covered with rubber or the like. The presser head is arranged directly over the top of the can 36 when shifted into the corresponding can holding device, as shown. The rod 76 is forced downwardly by the spring 77, and the downward movement of the rod is controlled by a roller 82, connected therewith, and arranged to engage a stationary cam segment 83, which is concentric with the shaft 25, and attached to the table top 20. The cam is arranged in the position shown, for a purpose to be more fully explained. The shaft 76 is splined in its bearing 78, so that it is free to reciprocate but cannot turn upon its longitudinal axis within the bearing and this will retain the arms 79 in the radial position.

Rigidly mounted upon the table 20 is a vertical post 84, having a flange 85, to support a spool 86, carrying a roll of tape 87, as shown. The roll is supported so that it may rotate upon its vertical axis and brake means is provided to regulate the turning movement of the roll and to prevent the same from rotating too freely. This brake means is shown as comprising resilient arm or spring 88, attached to the post 84, and carrying a roller 89, engaging the periphery of the roll. The tape may be of any suitable transparent or translucent material, such as "cellophane", of any desired width. The tape 87 is passed about an idler roller 90, rotatably supported to turn about a vertical axis and also about a guide roller 91, carried by an arm 92. The tape then passes to the tape holding device, to be described. The idler roller 90 is grooved and a companion adhesive applying roller 93, Figures 1, 2, 10 and 14, is arranged to substantially contact with the periphery of the idler roller and firmly engage the tape 87 passing between these rollers. The adhesive applying roller 93 has its axis of rotation disposed at an angle of about 45° with respect to the perpendicular and is rigidly mounted upon an inclined shaft 94 journalled in bearings 95. At its lower end, the shaft 94 has a bevelled gear 96, to rotate therewith and this bevelled gear is driven by a bevelled gear 97, driven by a vertical shaft 98. The adhesive applying roller 93 operates through a slot 99, formed in the top of a glue pot 100, which is in turn supported upon a pedestal 101. The pedestal 101 is provided at its top with guides 102 to receive flanges 103 carried by the glue pot so that the glue pot is horizontally adjustable toward and from the idler roller 90. By this means, the correct tension or frictional engagement between the adhesive applying roller 93 and the tape 87 is obtainable, and when this is found, the stop bolt 104 is adjusted to contact with the forward end of the flanges 103, and locked in this position by a nut 105. The glue pot may then be locked in the adjusted position

by a bolt or bolts 106. Should it be desired to remove the glue pot, this may be done by unscrewing the bolt or bolts 106, the glue pot, shaft 94 and bevelled gear 96, being removed as a unit. When this unit is again applied in position, the stop bolt 104 will limit the inward movement of the glue pot so that the adhesive applying roller 93 will have a proper engagement or pressure upon the tape 87, as is obvious. The roller 93 rotates in the adhesive or glue within the pot 100, 10 and applies the glue to one side of the tape 87, as it travels forwardly upon the idler roller 90. Means are provided for maintaining the coated portion of the tape under a suitable uniform tension, comprising a horizontally swinging arm 15 107, Figures 1 and 10, pivotally supported at 108. This arm 107 is swung in one direction by a retractile coil spring 109, connected with a stationary rod or post 110, through an adjustable element 111, such as a turnbuckle. At its free 20 end, the arm 107 carries a grooved roller 112, engaging with the tape 87 to shift it laterally and regulate its tension.

Arranged between the adhesive applying mechanism and the rotatable spider, is the mechanism which engages and holds the free end of the tape 87. This mechanism, Figures 7 and 9, includes a stationary bracket 113, arranged beneath the table top 20 and rigidly secured thereto. This bracket carries bearings 114 and 115, 30 receiving a vertical stub shaft 116, which is turned by a gear or pinion 117, engaging a reciprocating rack 118, operating within stationary guides 119. The means which operates the rack will be described later. Rigidly attached to the upper end of the stub shaft 116, Figures 1, 7, and 9, is an L-shaped arm or bracket 120, mounted to swing horizontally in an opening 121 in the table top, Figure 2. The arm 120 is provided at its upper end with apertured knuckles 122, as shown. Both knuckles 122 carry an inclined knuckle extension 123. A supporting or link structure is provided to support a suction operated tape holding nozzle 124. This supporting or link structure includes an upstanding link 125, including downwardly diverging spaced arms 126, connected at their lower ends by a knuckle or head 127, apertured for receiving a pin or pivot 128, passing through the apertured knuckles 122. The knuckle 127 has a horizontally extending finger 129 rigidly secured thereto, and this finger is arranged above and spaced from stationary bracket 130 formed integral with the horizontal swinging bracket 120. A compressible coil spring 131 is arranged between these elements and tends to swing the link 125 toward the spider. Pivotally connected with the knuckle extension 123 at 132 is a link 134 included in the supporting or link structure. The links 125 and 134 are pivotally connected at 135 60 and 136, respectively, Figures 7 and 8, with a horizontal arm 137, carrying a head 138 with which the suction nozzle 124 is preferably rigidly connected. The connection may be effected by means of guides 139, receiving a tongue 140, 65 effecting a sliding dove-tailed connection, with screws or bolts 141 serving to lock the parts together. The nozzle 124 has a recess 142, for engagement with the can 36. This recess is shown as curved to correspond to the contour 70 of the can, but the shape of the recess will vary as will be necessary with different shapes of cans. The recess 142 is of such a size that its wall engages one side of the can from a point 143 to a point 144, which last named point is in the 75

radial plane of the rotatable support which passes through the longitudinal axis of the can. The recess has a horizontal groove 145 to receive the rib 146 of the can so that the wall of the recess 5 may snugly engage with the can. The nozzle 124 is provided at its free end with a flat face 147, preferably vertical, but at an angle to the long dimension of the nozzle, and the nozzle has a port 148, which is vertically elongated so that it extends throughout substantially the entire width of the tape. This port is in communication with a coupling or nipple 149 having a flexible hose 150 connected therewith, and this hose is connected with a suitable source 10 of vacuum. This source of vacuum may be a vacuum pump including a cylinder 151', Figure 1, having a plunger 152' reciprocating therein. The link 125 is swung inwardly toward the spider by the spring 131, as stated, and means are provided to control this swinging movement. This 15 means comprises a lever 151, Figures 7 and 9, pivotally mounted between its ends at 152, upon the inner ends of the knuckle extensions 123. At its outer end the lever 151 carries a roller 153, 20 adapted to engage behind a transverse plate 154 rigidly attached to the arms 126, as shown. The lever 151 has its inner end swung upwardly by a retractile coil spring 155, so that the roller 153 will engage behind the plate 154. The inner end 25 of the lever 151 carries a roller 156 and this roller is adapted to be depressed by the cams 73. When the roller 156 is depressed, roller 153 travels upwardly and releases plate 154, whereby the spring 131 shifts the supporting or link structure inwardly toward the receptacle. The link or supporting structure will hold the arm 31 in a horizontal position when the link or supporting structure is shifted inwardly, whereby the nozzle 124 will have the wall of its recess 142 vertically 30 arranged to snugly press the flexible strip against the wall of the can, when the plate 154 is released, as stated. Before the roller 153 can again drop to the lower position behind this plate 154, the supporting or link structure must be shifted 35 outwardly, and to effect this shifting movement, the lug 129 is engaged by a depressing cam finger 157 rigidly mounted upon each of the spider arms 24.

Means are provided to cut the tape after the 40 same has been applied to the can in a manner to effect the overlapping of the ends of the cut tape. This means comprises, Figures 1, 2 and 12, a pedestal 158 located between the roll of tape 87 and the main spider. The pedestal is of course 45 rigidly mounted upon the table top 20 and is provided at its upper end with bearings 159 and 160. A horizontal shaft 161 is rotatable in these 50 bearings and is driven by a bevelled gear 162, driven by a bevelled gear 163, carried by a vertical rotatable shaft 164, as shown. The bearing 160 is provided with a reduced portion 165, for receiving a split collar 166, to be clamped thereon by means of a bolt 167. This collar carries a cone 168, which is ordinarily held stationary. 55 This cone is hollow and its outer end is open so that it receives a rotatable disk 169, rigidly attached to the rotatable shaft 161. A slide or carriage 170 has a slidable dove-tailed connection with the disk 169, for radial adjustment, and is clamped in the selected position to the same by bolts 171 or the like, operating through elongated slots 172. A radial arm 173 is rigidly attached to the slide or carriage 170, and has a bearing sleeve 174 clamped thereto. This bearing 60 sleeve rotatably holds a shaft 175, having a rotary

cutter 176, rigidly secured to one end thereof, and a bevelled friction disk 177, rigidly secured to its opposite end, and arranged to engage with the bevelled stationary cone 168. It is thus seen 65 that the cutter 176 will be rotated bodily about the cone 168 and will therefore be shifted to a position to contact with and cut the tape which has been properly applied to the can, the cutter also turning upon its axis as it bodily rotates about the cone 168. If it should be desirable to 70 adjust the rotary cutter 176 toward or from its point of cutting action with the tape, this can be effected by radially adjusting the slide 170, but this adjustment will vary the position that the friction disk 177 will have with relation to the 75 cone 168, and this will necessitate an adjustment of the cone longitudinally of the shaft 161, which can be effected by manipulation of the bolt 167, as is obvious.

Rolling or ironing means to act upon the tape 80 after it has been applied to the can and cut, and before the adhesive has been completely dried is provided, Figures 2 and 3. This means comprises a vertical bracket 178, arranged substantially opposite the said conveyor mechanism. This bracket is rigidly mounted upon the table top 20 and is provided with a vertical bearing 179, receiving a vertical rock shaft 180, having a sleeve 181 rigidly secured thereto. A crank 181 is rigidly secured to the lower end of the 85 sleeve 181'. This crank is connected with a retractile coil spring 182 attached to a stationary element or rod 183, as shown. Near its upper end, the sleeve 181' carries a horizontally swinging arm 184, provided at its free end with a roller 185, 90 preferably covered with rubber or some other material which is relatively stiff but somewhat resilient. This roller is grooved at 186 to receive the rib 146 of the can 136. The spring 182 will therefore retain the roller 185 in firm engagement with the tape applied to the can, and this can is now bodily rotated, whereby the roller will iron or roll out the applied tape, insuring a smooth and tight application of the tape to the can. In order that the arm 184 will be held 95 in a proper position prior to the approach of the can thereto, such arm is provided with a radial stop 187, rigidly attached thereto, adapted to engage with a stationary stop 188, secured to the bearing 179. While the apparatus shown 100 and described illustrates means for effecting one rolling action upon the applied tape, the invention is not necessarily restricted to such mode of operation, as additional rolling actions may be employed, if desired, and I also contemplate dispensing with the rolling action, in some instances.

The numeral 189 designates an inclined discharge chute, Figures 1 and 2, for receiving cans after the completion of the sealing operation. 105 This chute has its high end 190 so positioned that the bottom 34 of the pocket or can holding device travels in proximity to the same. A horizontally arranged sweep arm 191 is supported near the intake end 190 at an elevation above 110 the pocket 35 and will engage the can as it approaches the chute 189 and will transfer the can to the chute. The arrangement of the sweep arm 191 is such that a can will be moved thereby into the discharge chute for about two-thirds 115 of the length of the bottom of the can, before the can holding device passes the chute, the can then travelling down the chute by gravity.

Beneath the table 20 is a main horizontal drive shaft 192, journalled in fixed bearings 193, Fig- 120

ures 1 and 2. This shaft is preferably driven by a pulley 194, Figures 3 and 7, driven by a belt 195, driven by a smaller pulley 196, in turn driven by a motor 197. The action of the motor may be controlled by a switch 198, preferably arranged at the front of the table 20, Figure 2.

The vertical shaft 25 has an intermittent or step-by-step turning movement and is turned for one-fourth of a revolution each step. Between each step it is securely held or locked against turning movement. This is effected by means of a Geneva wheel mechanism, including a Geneva wheel 199, Figures 1 and 17, rigidly mounted upon the vertical shaft 25. This Geneva wheel has four radial slots 200, dividing the same into four equal segments 201, having curved peripheral portions 202. Arranged near and parallel with the vertical shaft 25 is a vertical shaft 203, Figure 1, having a bevelled gear 204 rigidly secured to its lower end, and this bevelled gear is engaged and driven by a bevelled gear 205, driven by the shaft 192. The shaft 203 is journalled in bearings 206 and is provided above this bearing with a locking disk 207, rigidly secured thereto and having substantially one-fourth of its area cut away, as shown at 207'. This locking disk travels into engagement with the curved peripheral portions 202, to lock the Geneva wheel against turning movement, during its interval of rest, and while the leading edge of the locking disk is travelling toward the Geneva wheel. The shaft 203 carries a radial crank 208, rigidly attached thereto and rotatable with the locking disk as a unit, and the longitudinal axis of this crank bisects the cut away segment 207' of the locking disk 207. The radial crank 208 carries at its outer end a roller 209, adapted to move into the radial slots 200 of the Geneva wheel, at the beginning of each step movement of the same. It is thus seen that the vertical shaft 25 will have a step-by-step movement and will be turned for one-fourth of a revolution during each step and will be locked against turning movement during the interval between the steps.

The turning sleeve 26 projects below the bearing 27, Figures 1, 3, and 17, and has a collar 210 keyed or otherwise attached thereto for rotation therewith and this collar carries a crank 211, Figures 1 and 17, pivotally connected with a link 212, in turn pivotally connected with a lever 213. This lever, Figure 17, is pivoted at its outer end to the frame 21, as shown at 214, and is provided between its ends with a roller 215, operating within a substantially circular cam groove 216, formed in the lower face of a horizontal disk 217, which is rigidly mounted upon the upper end of the vertical shaft 203. The continuous rotation of the shaft 203 will be transmitted to the cam disk 217, and the cam groove 216 and associated elements will impart to the sleeve 26 the proper oscillating movement, for turning the operating member 42 in a proper manner, to be more fully described.

The conveyor of the can feeding mechanism is driven by a sprocket wheel 218, Figures 1 and 3, rigidly mounted on the shaft 60, and this sprocket wheel is driven by a sprocket chain 219, extending downwardly to engage a sprocket wheel 220, rigidly mounted upon the main drive shaft 192.

Rotatably mounted upon the main drive shaft 192 is a sleeve structure 221, carrying a cam 223, a gear 224, and a second cam 225, all of these elements 221, 223, 224 and 225, being adapted to rotate as a unit. The sleeve 221 is capable of rotating upon the shaft 192 but cannot shift longitudinally thereon, and is provided at one end with a clutch head 226, for coaction with a clutch head 227, formed upon a sleeve 228, to which the pulley 194 is rigidly connected. The sleeve 228 is splined upon the shaft 192 to rotate therewith and be shifted longitudinally thereof by means of a fork 229, carrying rollers 230, operating in a groove 231. This fork is carried by the rear end of a lever 232, pivoted between its ends, as shown at 233, and this lever extends to the forward end of the machine and is equipped with a latch 234, for coaction with a latch quadrant 235, Figure 2. The cam 223 is arranged to have its periphery engage a roller 236, carried by a vertically swinging lever 237, the periphery of the cam having a dwell 238. The lever 237 is pivotally connected at its lower end, as shown at 239, with a stationary bracket 240. At its upper end, the lever 237 is pivotally connected with the rear end of the rack bar 118, as shown at 241, Figure 7. The lever 237 is swung forwardly toward the cam 223, by means of a retractile coil spring 242.

The gear 224 drives a gear 243, Figure 1, rigidly mounted upon a horizontal jack shaft 244, carried in suitable bearings 245. This jack shaft 25 has a worm gear 246, rigidly secured thereto, driving a worm gear 247, Figure 3, rigidly mounted upon a counter-shaft 248, operating suitable bearings 249. This countershaft is provided at its rear end with a worm gear 250, Figures 3 and 13, rigidly secured thereto and engaging a worm gear 251, rigidly secured to the lower end of the shaft 164. At the forward end of the shaft 248 is a worm gear 252, Figures 1, 2, 3, and 14, arranged to engage a worm gear 253, rigidly secured to the lower end of the vertical shaft 98.

The cam 225 has its periphery engaging a roller 254, Figure 1, carried by a vertically swinging lever 255, pivotally supported at its forward end, as shown at 256. The lever is swung upwardly by a retractile coil spring 257. The rear end of the lever is pivotally connected with a rod 258, connected with the plunger 152'. It is thus seen that the rotation of the cam 225 is employed to reciprocate the plunger 152', for providing a suitable degree of vacuum within the cylinder 151', at the proper time.

The operation of the machine is as follows:

The shaft 192 is driven by the motor, and clutch head 226 is driven by clutch 227, whereby all units of the machine are caused to operate. Each pocket of holding device 33 is brought up to the can feeding mechanism, and remains stationary at the feeding mechanism for a sufficient length of time to permit of the can being properly introduced into the same. When the can holding mechanism or pocket approaches the can feeding mechanism, Figures 3 and 11, cam 73 engages roller 70, and jaw 63 of the clamping mechanism is swung outwardly to release the leading can, as explained, and the continuously travelling belt 57 will now advance the row of cans and the leading can will enter the pocket or holding device 33. Upon the starting movement of the holding device from this position, cam 73 trips from roller 70 and the jaw 63 will again swing inwardly and hold the leading can against movement. Each holding device or pocket 33 is controlled in its turning movement upon its vertical axis throughout its entire cycle of operation, either by the curved rack 45 or by the curved locking-bar 46. When each holding device or pocket passes for a short distance beyond the rolling or ironing mechanism, its operation is controlled by the curved locking bar 46, which now engages the curved face 75

41 of the lug 40, this lug sliding around locking bar 46, whereby the holding device or pocket cannot turn upon its vertical axis, but bodily travels with the spider. At the time that the holding device or pocket 33 reaches the can feeding mechanism, the Geneva mechanism causes the spider to stop, as explained, and at this time the can holding device or pocket cannot turn upon its vertical axis and this is important as it insures 5 the pocket being in the proper radial position to receive the can from the feeding mechanism. The can holding device or pocket continues to be held against turning movement upon its longitudinal axis until it has been advanced to the 10 next position or step, at which the tape is applied to the can, and the holding device is turned upon its axis to wrap the tape about the can. When the can is moved into the holding device or 15 pocket in the can feeding position, the clamping mechanism is raised or inactive, as the roller 82 is 20 elevated, since it is travelling upon the cam 83. This is necessary, at the time that the can holding device or pocket is in the can receiving position, for the can could not otherwise be fed into 25 the same, and it is also necessary when the can is being discharged from the pocket or holding device, at the end of the cycle of operation, as will be explained more fully. The circumferential extent of the cam is clearly shown in Figure 2, 30 and it will be readily seen that the clamping device is held raised throughout that portion of the cycle of operation through which the cam extends. When the spider passes from the can receiving position to the next tape applying position, at a 35 point about midway between these two positions, the roller 82 passes from the cam 83 and the arm 79 will descend and the gripping element 81 will engage the top or lid of the can, which is forced down by the suitable pressure of the spring 77. 40 This clamping action effects two results. First, it properly seats or closes the lid or cover and maintains the same in the seated position until the tape is properly applied to the can, and secondly, it holds the can in the pocket in a secure 45 manner against accidental displacement. When the second position is reached, the can is radial with relation to the nozzle 124, as shown in Figure 5. Shortly before the second position is 50 reached, the cam 73 will depress roller 156 and raise roller 153, allowing the supporting or link structure to swing inwardly by virtue of the action of the spring 131, whereby suction nozzle 124 will receive the edge of the can in its recess 142, and the spring 131 will firmly press the nozzle 55 against the can. As should be stated at this time, the free end of the tape is engaging the flat face 147, and the plunger 152' is now travelling downwardly whereby the free end of the tape is held by the nozzle and passes between the face 142 and 60 the edge of the can. The tape has had adhesive applied to its surface. When the nozzle 124 thus begins to turn clockwise at the same rate of speed that the holding device 33 is turning upon 65 its vertical axis, as shaft 116 is now turned for that purpose by the rack-bar 118, and this movement continues until the nozzle and can has reached the position C, Figure 6. By the time the can has reached the position B, Figure 5, the operating member 42 begins to travel counter-clockwise 70 and its rack 45 will engage the gear 39, and turn this gear, and the can holding device or pocket 33 clockwise for effecting a complete rotation of the can. As before stated, the rack-bar 118 swung the bracket 120 clockwise so that the

nozzle 124 travelled with the can from position B, Figure 5, to position C, Figure 6, and rack-bar 118 continues this clockwise movement of the bracket 120 until the nozzle reaches position C, at which time the nozzle 124 moves radially 5 from the can to disengage the same, which is effected by the cam finger 157 depressing lug 129, allowing roller 153 to drop back behind plate 154, again holding the toggle structure in the outer radial position. Shaft 116 is concentric 10 with shaft 32, when shaft 32 turns bracket 120 about the can and can holding device. The rack bar 118 now reverses its movement and swings the bracket 120 counter-clockwise, returning the nozzle to the normal starting position, as indicated 15 in Figure 4. Before or about the time the cam finger 157 depressed lug 129 to swing nozzle 124 from the can, plunger 152' started upon its upward movement releasing the vacuum in the nozzle 124 so that the nozzle would release the tape. 20 When nozzle 124 reaches the starting position, Figure 4, its flat face 147 again contacts with the tape 87. While the nozzle 124 is being returned to the normal starting position, the turning of the can was continued until a complete revolution 25 was made. Particular attention is called to the fact that the tape 87 having the adhesive thereon is held taut at a substantially uniform tension during the entire revolution of the can, and this aids materially in the proper application of the 30 tape. This uniform tension is effected by the brake roller 89 acting upon the roll of tape to retard its rotation, while the tape is fed entirely by the turning of the can while the tape is acted upon by the tension roller 112. Just as the can has 35 completed its rotation for applying the tape thereto, the plunger 152' again starts its descent to create vacuum within the nozzle 124 and this nozzle will again grip the tape, now in contact therewith, which must be done before the tape is cut. 40 This cutting operation occurs immediately after the nozzle thus grips the tape and this is effected by the rotary cutter 176 bodily moving into engagement with the tape at about the point D, Figure 12, the cutter again moving from such tape. 45 The cut tape which is now applied to the can at the junction of the lid or cover and body, has its end slightly overlapped. These operations have occurred while the spider 22 was stationary. The Geneva gearing again turns the spider for one-fourth of a revolution to move the can from the tape applying position to the third or rolling or ironing position. When the can reaches the ironing or rolling position, the operating member 42 is then turned counter-clockwise, while the spider 50 remains stationary, and this causes the can holding device or pocket 33 to be rotated clockwise, whereby the can is turned for a complete revolution and the roller 185 presses upon, irons, or rolls the applied tape 87 before the adhesive has completely dried, thereby effecting a complete and firm seal between the tape, can, and top or cover. The tape also securely connects the top or cover with the body of the can and effects an air-tight 55 joint. When the can has reached the third or rolling position, the clamping mechanism including the head 80, is still in the lowered position, holding the can in place within the pocket. The Geneva gearing again turns the spider for about one-fourth of a revolution and the can and pocket 60 holding the same is moved to the fourth position. As the can and holding device or pocket 33 approaches the fourth position, the roller 82 rides up upon the cam 83 and the clamping member 80 is elevated to release the can. When the 65

Geneva gearing moves the can from the fourth position toward the first position, the can is engaged by the arm 191 and is shifted generally radially out of the holding device or pocket 33 into the 5 inclined chute 189 and will gravitate downwardly therein. By the time this holding device or pocket 33 travels from the fourth position to the first position, the cycle of operation is completed and the leading can is again fed into each pocket as 10 it reaches the feeding position, and the several modes of operation occur with each pocket in succession, at the several positions.

The complete movements of the operating member 42 and receptacle holding device 15 throughout the complete cycle of operation will now be given. In Figure 2, the receptacle holding device 33 may be regarded as in the first or can feeding position, while the spider is at rest. When in this position, with the spider at rest, 20 the operating member 42 is now turning counter-clockwise from the starting position, shown in Figure 2, and this turning movement is throughout one-fourth of a revolution, since the locking bar 46 extends throughout slightly more than 25 one-half of the circumference of the operating member and the rack bar 45 does not extend throughout quite one-half of the circumference. This counter-clockwise turning movement of the operating member 42 will bring the rack-bar 30 into mesh with the gear 39 of the receptacle holding device 33 in position one, while the locking bar disengages face 41, and when this occurs, the spider starts on its next step movement toward the second or strip applying position. While this 35 is taking place, the operating member 42 turns clockwise at the same rate of speed as the spider and the receptacle holding device does not turn upon its axis, although the gear 39 is engaging the rack-bar 45. When the receptacle holding 40 device reaches the second position, the operating member 42 is again in the normal starting position, Figure 2, and the rack-bar still engages one tooth of the gear 39, as more clearly shown in Figure 12. The spider is now at rest with the 45 receptacle holding device in the second position, and the operating member 42 again turns counter-clockwise for one-fourth of a revolution, and this turns the receptacle holding device 33 clockwise for a complete revolution. The spider now 50 starts on its next step, and the rack-bar 45 is still in mesh with the gear 39 and operating member 42 is again turned clockwise with the spider substantially at the same speed and when the operating member 42 again reaches the 55 normal starting position, Figure 2, the receptacle holding device is in the third or ironing position and is brought to rest, as the spider stops. The operating member 42 is again turned counter-clockwise for one-fourth of a revolution and the 60 rack-bar 45 turns gear 39 and the receptacle is rotated while in engagement with the ironing roller. As the end of the counter-clockwise movement of member 42 is reached, rack-bar 45 disengages gear 39 and locking bar 46 engages face 65 41 of lug 40. The spider now starts on its next step and moves receptacle holding device 33 toward the fourth position, and the operating member 42 again travels clockwise substantially at the same rate of speed with the spider and when 70 the receptacle holding device 33 reaches the fourth position the operating member 42 is in the starting position, Figure 2. When the spider stops with the receptacle holding device in the fourth position, the operating member turns 75 counter-clockwise for one-fourth of a revolution

and the locking bar 46 slides upon the face 41. When the spider turns for the next step from the fourth position to the first or receptacle feeding position, the operating member 42 turns clockwise for one-fourth of a revolution at the same rate of speed as the spider until the spider 5 stops and the receptacle holding device is again in the first position, at which time the operating member 42 again turns counter-clockwise for one-fourth of a revolution to bring the rack-bar 10 45 in mesh with the gear 39 of the receptacle holding device in the first position, and the cycle of operation is repeated.

While I have shown my machine as embodying four pockets or holding devices 33, it will be 15 understood that this number may be varied as the same may be increased or decreased, as desired. Further, the invention is in no sense restricted to the treatment of cans of the precise shape shown, as cans of various shapes may be treated, such 20 as round cans, square cans or the like. This would require but a slight modification of the machine, residing principally in changing the shape of the can holding devices and the shape of the recesses in the nozzle. Further, the invention 25 is in no sense restricted to applying the tape to cans formed of tin or metal, as the same may be used to apply tape in a similar manner to various receptacles having closure elements, which receptacles may be formed of porcelain or 30 other non-metallic substances.

It is to be understood that the form of my invention herewith shown and described is to be taken as a preferred example of the same and that various changes in the shape, size, and arrangement of parts may be resorted to, without departing from the spirit of my invention or the scope of the subjoined claims.

Having thus described my invention, I claim:

1. In a machine for applying a flexible strip 40 to a receptacle, a travelling support, a receptacle holding device mounted upon the travelling support and adapted to be turned upon its axis with relation to the travelling support, means to feed the receptacle into the receptacle holding device, 45 means to pay out the strip and regulate its tension, a member having detachable connection with the end of the strip and movable toward the receptacle to bring the strip into contact with the side of the receptacle, means to move the member 50 with the receptacle holding device when such device is turned, and means to cause an adhesive to be applied to the face of the strip next to the receptacle.

2. In a machine for applying a flexible strip 55 to a receptacle, a travelling support, a device mounted upon the support to receive and hold the receptacle on end and to turn the same upon its longitudinal axis with relation to the support, means to pay out the strip and regulate its tension, a member having detachable connection with one end of the strip and movable to bring the strip into contact with the side of the receptacle, means to move the member in a curved path so that it remains adjacent to the receptacle 60 when the receptacle is turned upon its axis for a portion of its turning movement, means to cause an adhesive to be applied to the face of the strip next to the receptacle, and means to cut that portion of the strip after it is wrapped upon the 65 receptacle from the remainder of the strip.

3. In a machine for applying a flexible strip to a receptacle, means for supporting and holding the receptacle and turning the same upon its axis of rotation, a suction operated nozzle for 70 75

- holding the flexible strip, means to move the nozzle toward the supporting means so that the flexible strip is brought into contact with the side of the receptacle and held in such contact 5 during a portion of the turning movement of the receptacle, means for regulating the feeding movement of the flexible strip, and means for causing an adhesive to be applied to the face of the strip next to the receptacle.
- 10 4. In a machine for applying a flexible strip to a receptacle, a travelling support, a plurality of spaced receptacle holding devices mounted upon the support to travel therewith and pivoted thereon to turn upon their axes of rotation with relation thereto, means to effect a step-by-step travelling movement of the support, a trough arranged near the travelling support for receiving a plurality of receptacles, means to feed the receptacles longitudinally of the trough toward the 15 travelling support, a clamping device normally engaging the leading receptacle to prevent its feeding movement, means actuated by the travelling support when each holding device is brought to a position adjacent to the trough for operating the clamping device so that it disengages the leading receptacle, a device arranged near the travelling support and spaced from the trough and engaging the free end portion of the flexible strip and adapted to apply the same to the side of 20 the receptacle when such receptacle is shifted in proximity thereto, means coacting with the strip engaging device for supporting the strip so that it will be wrapped about the receptacle when such receptacle is turned upon its axis, means to 25 cause each receptacle holding device and the strip engaging device to turn in unison about a common axis of rotation when the free end of the strip is applied to the receptacle, means for causing an adhesive to be applied to the face of the 30 strip next to the receptacle, and means to cut that portion of the strip after it is applied to the receptacle from the remainder of the strip.
- 35 5. In a machine for applying a flexible strip to a receptacle, a substantially horizontal rotatable support, a plurality of circumferentially spaced holding devices pivotally mounted upon the rotatable support to travel therewith and turn upon their substantially vertical axes with relation thereto, each holding device being adapted to receive a receptacle on end, means to feed a receptacle to each holding device when shifted to a selected position, a plurality of pressure devices corresponding in number and arrangement to the receptacle holding devices to engage with the closure elements thereof to seat the same, upstanding reciprocatory rods connected with the rotatable support and carrying the pressure devices, resilient means to force the rods downwardly, a relatively stationary cam extending about the axis 40 of rotation of the rotatable support and serving to raise the rods during a portion of their travel with the rotatable support, means engaging one end portion of the flexible strip and serving to apply the same to the side of the receptacle when each 45 receptacle is shifted to the next selected position, means cooperating with the strip engaging means to cause the flexible strip to be wrapped about the receptacle when it is turned upon its axis, means to turn each holding device upon its axis when the flexible strip is applied to the receptacle 50 therein, means to cause an adhesive to be applied to the face of the flexible strip next to the receptacle, and means to cut that portion of the flexible strip after it is wrapped about each receptacle from the remainder of the strip.
- 55 6. In a machine for applying a flexible strip to a receptacle, a rotatable support, a plurality of spaced receptacle holding devices pivotally mounted upon the support to travel therewith and turn upon their axes with relation thereto, receptacle feeding mechanism arranged near the rotatable support, strip applying mechanism arranged near the rotatable support and circumferentially spaced from the feeding mechanism, means to effect a step-by-step movement of the rotatable support so that each receptacle holding device is brought to the feeding mechanism and to the strip applying mechanism in succession, pressure applying mechanism rotatable with the rotatable support and adapted to force the closure elements of the receptacles downwardly into proper seating engagement with the receptacles, a relatively stationary cam for controlling the action of the pressure applying mechanism, said cam holding the pressure applying mechanism elevated during a portion of its rotation, means for causing an adhesive to be applied to the surface of the strip next to the receptacle, and means to cut at a point adjacent to the receptacle that portion of the strip after it is applied to each receptacle from the remainder of the strip. 60

- 65 7. In a machine for applying a flexible strip to a receptacle, a rotatable support, a plurality of circumferentially spaced receptacle holding devices pivotally mounted upon the support to travel therewith and turn upon their axes in relation thereto, receptacle feeding mechanism arranged near the rotatable support, a flexible strip applying mechanism arranged near the rotatable support in advance of the feeding mechanism, flexible strip ironing mechanism arranged in advance of the strip applying mechanism and near the rotatable support, means to effect a step-by-step movement of the rotatable support to bring each receptacle holding device in proximity to 65 said mechanisms in succession, means carried by the rotatable support for setting into action the feeding mechanism and the strip applying mechanism when each holding device is brought into proximity to the same, and means to cut that portion of the flexible strip after it is wrapped about each receptacle from the remainder of the strip. 70
- 75 8. In a machine for applying a flexible strip to a receptacle, a rotatable support, a plurality of circumferentially spaced receptacle holding devices pivotally mounted upon the support, receptacle feeding mechanism arranged near the rotatable support, a flexible strip applying mechanism arranged near the rotatable support in advance of the feeding mechanism, flexible strip ironing mechanism arranged near the rotatable support in advance of the applying mechanism, means to effect step-by-step movement of the rotatable support to bring each receptacle holding device in succession in proximity to said mechanisms, automatic means to set into action the feeding mechanism and the applying mechanism when each receptacle holding device is brought into proximity thereto, means to turn each holding device upon its axis with relation to the rotatable support when each holding device is brought into proximity to the applying mechanism and the ironing mechanism, and means to cut that portion of the flexible strip after it is wrapped about each receptacle from the remainder of the strip. 75
- 80 9. In a machine for applying a flexible strip to a receptacle, a rotatable support, a plurality of circumferentially spaced receptacle holding devices pivotally mounted upon the support to travel therewith and turn upon their axes with relation thereto, receptacle feeding mechanism arranged near the rotatable support, strip applying mechanism arranged near the rotatable support and circumferentially spaced from the feeding mechanism, means to effect a step-by-step movement of the rotatable support so that each receptacle holding device is brought to the feeding mechanism and to the strip applying mechanism in succession, pressure applying mechanism rotatable with the rotatable support and adapted to force the closure elements of the receptacles downwardly into proper seating engagement with the receptacles, a relatively stationary cam for controlling the action of the pressure applying mechanism, said cam holding the pressure applying mechanism elevated during a portion of its rotation, means for causing an adhesive to be applied to the surface of the strip next to the receptacle, and means to cut at a point adjacent to the receptacle that portion of the strip after it is applied to each receptacle from the remainder of the strip. 85

- devices pivotally mounted upon the support to travel therewith and turn upon their axes with relation thereto, receptacle feeding mechanism arranged near the rotatable support, a flexible strip applying mechanism arranged near the rotatable support in advance of the feeding mechanism, means to effect a step-by-step movement of the rotatable support to bring each receptacle holding device in succession in proximity to said mechanisms, automatic means to actuate the feeding mechanism and the applying mechanism when each receptacle holding device is brought into proximity thereto, means to turn each holding device upon its axis when brought into proximity to the applying mechanism, means to cause the applying mechanism to turn with the holding device, and means to cut that portion of the flexible strip after it is wrapped about each receptacle from the remainder of the strip.
10. In a machine for applying a flexible strip to a receptacle, a receptacle holding device, a device to hold the strip, means to actuate the strip holding device so that the strip is brought into engagement with the receptacle, and means to turn the receptacle holding device and the strip holding device in unison so that the receptacle is turned and the strip wrapped about such receptacle.
11. In a machine for applying a flexible strip to a receptacle, a receptacle holding device, means to support the flexible strip including an element for movement in close relation to the receptacle, means to shift the element toward the receptacle to bring the strip into engagement with the receptacle, means to turn the receptacle holding device upon its axis, and means to move the element about the axis of rotation of the holding device.
12. In a machine for applying a flexible strip to a receptacle, a receptacle holding device, means to support the flexible strip including an element for movement in close relation to the receptacle, means to turn the receptacle holding device upon its axis, and means to move the element toward the receptacle for applying the strip to the receptacle and causing the element to travel circumferentially with the receptacle when the receptacle is turned.
13. In a machine for applying a flexible strip to a receptacle, a support, a supporting element pivoted upon the support to turn on its axis, a device movably mounted upon the supporting element for holding engagement with the flexible strip and shiftable toward the turning axis of the supporting element, means cooperating with the device for feeding the flexible strip, a rotatable receptacle holding device, means for supporting the receptacle holding device so that its axis of rotation is concentric with the turning axis of the supporting element, means to turn the supporting element, and means to rotate the receptacle holding device.
14. In a machine for applying a flexible strip to a receptacle, a support, a supporting element pivoted upon the support to turn on its axis, a device pivotally mounted upon the supporting element for holding engagement with the flexible strip and shiftable toward the turning axis of the supporting element, means cooperating with the device for feeding the flexible strip, a spring to swing the pivoted device in one direction, a releasable latch for holding the swinging device against such movement, a rotatable receptacle holding device, means for supporting the receptacle holding device so that its axis of
- rotation is concentric with the turning axis of the supporting element, means actuated by the last named supporting means to trip the releasable latch, and means to turn the supporting element upon its axis and rotate the receptacle holding device upon its axis.
15. In a machine for applying a flexible strip to a receptacle, as a sub-combination, a pivoted support, a link structure pivotally mounted upon the support, a suction nozzle carried by the link structure, automatic means to shift the link structure in one direction when released, and a releasable latch for holding the link structure against such shifting movement.
16. In a machine for applying a flexible strip to a receptacle, as a sub-combination, a pivoted support, a link structure pivotally mounted upon the support, a suction nozzle carried by the link structure, automatic means to shift the link structure from the set position when released, releasable means for holding the link structure in the set position, means to actuate the releasable means, and means to reset the link structure.
17. In a machine for applying a flexible strip to a receptacle, a suction nozzle having a strip holding face and a port extending through such face, said nozzle having a recess for receiving a portion of the receptacle, and movable means for supporting the nozzle.
18. In a machine for applying a flexible strip to a receptacle, a nozzle having a strip holding face and a port extending through such face, and movable means for supporting the nozzle.
19. In a machine for applying a flexible strip to a receptacle, a rotatable support, a plurality of receptacle holding devices pivotally mounted upon the rotatable support to travel therewith and turn upon their axes with relation thereto, receptacle feeding mechanism arranged near the rotatable support, a strip applying mechanism arranged near the rotatable support in advance of the receptacle feeding mechanism, strip ironing mechanism arranged near the rotatable support in advance of the strip applying mechanism, means to impart a step-by-step movement to the rotatable support to bring each receptacle holding device in succession in proximity to each of said mechanisms, and means to positively hold each receptacle holding device against turning movement upon its axis when it is travelling with the rotatable support from one mechanism to the other and to rotate such holding device upon its axis when the rotatable support is stationary and the holding device is in proximity to the strip applying mechanism or the ironing mechanism.
20. In a machine for applying a flexible strip to a receptacle, a rotatable support, a plurality of receptacle holding devices pivotally mounted upon the rotatable support, a gear and locking wheel connected with each receptacle holding device to control its turning movement, the locking wheel having a locking face, a control member including a circularly curved rack-bar and a circularly curved locking bar which are substantially oppositely arranged, the rack-bar engaging the gear and the locking bar the locking face of the locking wheel, means to pivotally support the control member in concentric relation to the rotatable support, means to effect a step-by-step turning movement of the rotatable support, and means to oscillate the control member.
21. In a machine for applying a flexible strip to a receptacle, a rotatable support, a plurality of receptacle holding devices pivotally mounted upon the rotatable support, a gear and locking wheel connected with each receptacle holding device to control its turning movement, the locking wheel having a locking face, a control member including a circularly curved rack-bar and a circularly curved locking bar which are substantially oppositely arranged, the rack-bar engaging the gear and the locking bar the locking face of the locking wheel, means to pivotally support the control member in concentric relation to the rotatable support, means to effect a step-by-step turning movement of the rotatable support, and means to oscillate the control member.

to a receptacle, a rotatable support, a shaft rotatably mounted thereon, a receptacle holding device mounted upon the shaft, a gear and locking wheel rigidly mounted upon the shaft at 5 different elevations, the locking wheel having a concave locking face, a control member including a circularly curved rack-bar and a circularly curved locking bar movable as a unit and arranged in different elevations, the rack-bar en- 10 gaging the gear and the locking bar the circularly curved locking face, and means for pivotally supporting the control member in concentric relation to the rotatable support.

22. In a machine for applying a flexible strip 15 to a receptacle, as a sub-combination, a pivoted control member including a rim embodying a curved rack-bar and a curved locking bar ar- ranged substantially opposite each other and means to turn the control member in opposite 20 directions.

23. In a machine for applying a flexible strip to a receptacle, as a sub-combination, a pivoted control member including a rim embodying a curved rack-bar and a curved locking bar ar- 25 ranged substantially opposite each other and in different planes and means to turn the control member in opposite directions.

24. In a machine for applying a flexible strip to a receptacle, a receptacle holding device, a 30 support, means to pivotally support the receptacle holding device and the support so that they may turn about a common axis, means to turn the receptacle holding device and support about the common axis, a supporting element 35 pivoted upon the support, a head carried by the supporting element to press the flexible strip against the receptacle, a spring to swing the supporting element in one direction, a releasable latch device for holding the supporting element 40 against swinging movement by the action of the spring, means to trip the latch device, and means to reset the supporting element.

25. In a machine for applying a flexible strip to a receptacle, a receptacle holding device, a 45 support, means to pivotally support the receptacle holding device and the support so that they may turn about a common axis, a supporting element pivoted upon the support, a member carried by the supporting element to press the 50 flexible strip against the receptacle, means to swing the pivoted supporting element toward the receptacle, and means to swing the pivoted supporting element from the receptacle.

26. In a machine for applying a flexible strip 55 to a receptacle, a receptacle holding device, a support, means to pivotally support the receptacle holding device and the support in end-to-end relation so that they may turn about a common axis, means to turn the receptacle holding 60 device and support about the common axis, a member to press the flexible strip against the receptacle, means to movably mount the member upon the support so that the member is movable with relation to the support toward and 65 from the receptacle, and means to move the member toward and from the receptacle.

27. In a machine for applying a flexible strip to a receptacle, a receptacle holding device, a support, means to pivotally support the receptacle holding device and the support in end-to-end relation so that they may turn about a common axis, means to turn the receptacle holding device and support about the common axis, a member having a contact face having a contour 70 corresponding to the contour of the receptacle

and serving to press the flexible strip against the receptacle, means to movably mount the member upon the support, and means to move the member with relation to the support toward and from the receptacle. 5

28. In a machine for applying a flexible strip to a receptacle, as a sub-combination, a pivoted support, means to turn the support upon its pivot, a supporting element pivotally mounted upon the pivoted support, a head carried by the pivoted supporting element and serving to press the flexible strip against the receptacle, and means to move the pivoted supporting element in opposite directions with relation to the support. 10

29. In a machine for applying a flexible strip 15 to a receptacle, as a sub-combination, a pivoted support, means to turn the pivoted support upon its pivot, an arm pivotally mounted upon the pivoted support, a head secured to the arm and serving to press the flexible strip against the receptacle, a spring to move the pivoted arm toward the receptacle, a latch device to hold the pivoted arm against movement by the spring, means to trip the latch device, and means to reset the pivoted arm. 20

30. In a machine for applying a flexible strip to a receptacle, a travelling support, a plurality of spaced receptacle holding devices mounted upon the travelling support to travel therewith and pivoted thereon to turn upon their axes 30 with relation thereto, means to move the travelling support, a trough arranged near the travelling support for receiving a plurality of receptacles, means to feed the receptacles through the trough toward the travelling support, means 35 for controlling the movement of the leading receptacle so that it is introduced into the holding device when such holding device is brought to the receptacle receiving position, means operating in timed order with the travelling support 40 for actuating the controlling means, a device adapted to press the flexible strip against the receptacle when the receptacle is brought to a selected position, means coacting with the device for supporting the strip so that it will be 45 wrapped about the receptacle when such receptacle is turned upon its axis, means to cause the receptacle holding device and strip pressing device to turn in unison about their axes and the strip pressing device to travel circumferentially 50 with the receptacle holding device, and means for causing an adhesive to be applied to the face of the strip next to the receptacle.

31. In a machine for applying a flexible strip 55 to a receptacle and its closure element, a substantially horizontal rotatable support, a plurality of circumferentially spaced substantially vertical receptacle holding devices pivotally mounted upon the rotatable support to travel therewith and turn upon their axes with relation 60 thereto, means to feed a receptacle to each holding device when the holding device is shifted to a selected position, a plurality of pressure devices corresponding in number and arrangement to the receptacle holding devices to engage with the closure elements of the receptacles to seat the same, reciprocating rods connected with the rotatable support and carrying the pressure devices, resilient means to force the rods downwardly, a relatively stationary cam track serving to retain the 70 reciprocating rods raised during a portion of their travel with the rotatable support, means serving to press the flexible strip against the side of the receptacle when the receptacle is shifted to a selected position, means cooperating with the strip 75

- pressing means to cause the strip to be wrapped about the receptacle when the receptacle is turned upon its axis, and means to turn each receptacle holding device upon its axis to cause the flexible strip to be wound thereon. 5
32. In a machine for applying a flexible strip to a receptacle and its closure element, a substantially horizontal rotatable support, a plurality of circumferentially spaced substantially vertical receptacle holding devices pivotally mounted upon the rotatable support to travel therewith and turn upon their axes with relation thereto, means to feed a receptacle to each holding device when the holding device is shifted to a selected position, 10 10
- 15 a plurality of pressure devices corresponding in number and arrangement to the receptacle holding devices to engage with the closure elements of the receptacles to seat the same, reciprocatory rods connected with the rotatable support and carrying the pressure devices, resilient means to force the rods downwardly, a relatively stationary cam track serving to retain the reciprocatory rods raised during a portion of their travel with the rotatable support, means serving 20 15
- 25 to press the flexible strip against the side of the receptacle when the receptacle is shifted to a selected position, means cooperating with the strip pressing means to cause the strip to be wrapped about the receptacle when the receptacle is turned 30 20
- 30 upon its axis, means to turn each receptacle holding device upon its axis to cause the flexible strip to be wound thereon, and means to cause the strip pressing means to travel bodily circumferentially with the receptacle during a portion of its turning movement. 35
33. In a machine for applying a flexible strip to a receptacle, a receptacle holding device, a strip pressing device, means to actuate the strip pressing device so that it presses the strip against the receptacle, means to turn the receptacle holding device upon its axis, and means to cause the strip pressing device to travel in a curved path about the axis of rotation of the receptacle holding device and in unison with the turning movement of the receptacle holding device so that the strip pressing device is stationary with relation to the receptacle when pressing the strip against the same and the strip is wound about the receptacle when the receptacle is turned upon its axis. 40 30

to a receptacle, a substantially horizontal travelling support, a plurality of substantially vertical receptacle holding devices pivotally mounted upon the support to travel therewith and turn 5 upon their axes with relation thereto, each device having a bottom and side and an opening at its top, said side having a receptacle inlet passage, each holding device moving with the travelling support to a receptacle receiving position, 10 a strip winding position, and a receptacle discharge position, receptacle feeding means arranged at the receptacle receiving position, means to positively hold each receptacle holding device against turning movement upon its axis 15 when travelling with the travelling support from proximity to the receptacle discharge position to the receptacle receiving position so that the receptacle inlet passage of the receptacle holding device will be arranged next to the receptacle 20 feeding means when such holding device reaches the receptacle receiving position, means to press the flexible strip against the receptacle so that it is wound upon the receptacle when the receptacle is turned upon its axis, means to turn each 25 receptacle holding device upon its axis when it reaches the strip winding position, a pressure applying device operating through the opening at the top of each receptacle holding device to engage with the end of the receptacle, and 30 means to operate the pressure applying device for holding and releasing the receptacle.

40. In a method of applying a flexible strip to a receptacle, the steps of pressing the end portion of the flexible strip into contact with the 35 side of the receptacle, holding the receptacle on end and turning the receptacle upon its axis for substantially a complete revolution while continuing to press the end of the strip against the receptacle for a portion of the turning movement of the receptacle for wrapping the strip 40 about the receptacle in the presence of an adhesive, controlling the paying out movement of the strip during the wrapping operation to place the strip under tension, holding the strip at a 45 point adjacent to the receptacle after the completion of the wrapping operation, and then cutting the strip between the point of holding and the receptacle.

41. In a machine for applying a flexible strip 50 to a receptacle, a travelling support, a plurality of receptacle holding devices mounted upon the travelling support to move therewith and turn upon their axes with relation thereto, means to press the end portion of the flexible strip into 55 contact with the side of the receptacle when the holding device is shifted to a selected position and to release the flexible strip and again holding the strip at a point near and spaced from the receptacle, means to turn each holding device 60 upon its axis to wind the strip thereon, and means to cut the strip after being wound upon upon the receptacle and at a point between the receptacle and the strip holding means.

42. The method of applying a flexible strip to 65 a receptacle, comprising the steps of supporting the receptacle, holding the strip near its free end and pressing the strip against the side of the receptacle, turning the receptacle upon its axis to wind the pressed strip thereon while continuing the holding and pressing action, releasing 70 the holding and pressing action, then holding the strip at a point near and spaced from the receptacle after the winding action, and cutting the strip after the winding action and during the last named holding action at a point between the

point of the last named holding action and receptacle.

43. In a machine for applying a flexible strip to a receptacle, means to support the receptacle, a strip holding element, means to move the strips holding element so that it holds the strip against the side of the receptacle and subsequently releases such holding and pressing action and then holds the strip at a point near and spaced from the receptacle after the winding operation, 10 means to turn the support when the strip is pressed upon the side of the receptacle to wind the strip thereon, and means operated after the winding action and during the last named holding action to cut the strip between the point 15 of the last named holding action and receptacle.

44. A machine of the class described, comprising a movable carrier, means for feeding capped containers one by one to said carrier at one station to be moved as said carrier is moved, means 20 for removing said containers from said carrier at another station, and means acting while each container is carried by said carrier to apply sealing material in position to seal each cap to its container.

45. In a machine for applying a flexible strip or tape to a receptacle, a turning supporting member, a spring actuated arm pivoted upon the supporting member, a head carried by the arm to engage the strip and hold the same upon the 30 receptacle, a latch device to hold the pivoted arm against movement, means to trip the latch device, means to reset the pivoted arm, and means for holding a can in cooperative relation to the turning supporting member and turning the supporting member and can holding means upon 35 their axes.

46. In a machine for applying a flexible strip or tape to a receptacle, a receptacle holding device to receive the end of the receptacle, a supporting member arranged in spaced end-to-end relation with the receptacle holding device, means carried by the supporting member and movable into engagement with the strip and forcing the strip into engagement with the side of the receptacle, and means to turn the receptacle holding device and the supporting member upon their axes.

47. In a machine for applying a flexible strip or tape to a receptacle, a receptacle holding device to receive the end of the receptacle, means for exerting pressure upon the opposite end of the receptacle for retaining the same in place within the holding device, a supporting member arranged near and spaced from the receptacle holding device, means carried by the supporting member and movable into engagement with the strip for forcing the strip into engagement with the side of the receptacle, and means to cause the receptacle holding device and supporting 60 member to turn about a common axis.

48. In a machine for applying a flexible strip to receptacles, means for guiding the flexible strip and applying an adhesive to one side of the same, a moving support, a plurality of receptacle holding devices mounted upon the moving support in spaced relation and movable with the moving support in succession to a strip contacting position, a device coating with each receptacle holding device for pressing the strip to the 70 receptacle, means to turn each receptacle holding device upon its axis when moved a selected distance beyond the strip contacting position, a strip gripping device for use with each receptacle holding device, and means to cut the strip. 75

49. In a machine for applying a flexible strip or tape to a receptacle, a supporting member, an arm pivotally mounted upon the supporting member, a head carried by the arm to engage the strip and move the same into engagement with the receptacle, and means to move the arm in opposite directions.

50. In the method of applying a flexible sealing strip in overlapping relation to a container and its closure element, the steps of pressing the leading end of the flexible strip into contact with the side of the container and continuing such pressing action while turning the container for a portion of a revolution to wind the strip around

the container, and effecting a retarding paying out action of the strip during the winding action for placing the strip under tension.

51. In the method of applying a flexible sealing strip in overlapping relation to a container and its closure element, the steps of pressing the flexible strip into contact with the side of the container and continuing such pressing action while turning the container to wind the strip upon the container, effecting a retarding paying out action of the strip during the winding action for placing the strip under tension, and severing the strip. 10

THOMAS H. NIFONG.
